LASTING MACHINE

Leroy Farnum, Swampscott, and Lloyd G. Miller,
Beverly, Mass., assignors to United Shoe Ma-
chinery Corporation, Borough of Flemington,
N. J., a corporation of New Jersey

Application January 17, 1940, Serial No. 314,262

17 Claims. (Cl. 12—12)

This invention relates to lasting machines, and is herein illustrated as applied to a machine of the same general character as disclosed in United States Letters Patent No. 1,843,232, granted on February 2, 1932, upon an application of B. Jorgensen, but modified in certain respects as further disclosed mainly in Letters Patent No. 2,026,539, granted on January 7, 1936, also upon an application of B. Jorgensen. It is to be understood, however, that in various aspects the invention is not limited to machines of the type therein disclosed.

Machines of the above-mentioned type are commonly used in lasting tennis shoes or the like having uppers of textile fabric and rubber shoe bottom parts which are vulcanized while the shoes are on their lasts. Such a machine includes a toe former which extends around the toe end and along portions of the sides of the upper and 20 wipes the upper heightwise of the last, overlaying members which lay or wipe the margin of the portions of the upper embraced by the toe former inwardly over an insole on the last into position to adhere to the insole, and side-lasting devices 25 which conform the upper to the sides of the last and lay its margin inwardly over the insole first along the shank portion of the shoe and thereafter in locations nearer the toe end of the shoe adjacent to the toe former and the above-mentioned overlaying members. An object of the present invention is to provide a construction such as to produce improved results along the sides of the forepart, and more particularly, in 30 one aspect, to afford better insurance than heretofore against the formation of any upstanding wrinkles in the margin of the upper over the insole between the above-mentioned overlaying members and the side-lasting devices. Treatment which shoes of the above-mentioned type ordinarily receive between the lasting operation and the laying of the outsole render it especially desirable that no such wrinkles be present. For the purposes in view the machine herein shown is provided with novel means constructed and arranged to bridge any space that there may be along the margin of the upper between the above-mentioned overlaying members and the side-lasting devices and to be pressed upon the margin of the upper by those members and devices. As 40 illustrated, flexible straps are arranged to extend heightwise of the shoe between the toe former and portions of the sides of the upper and to extend also into positions where they are overlapped and forced inwardly over the insole against the margin of the upper by the above-mentioned

overlaying members and are thereafter overlapped and pressed upon the margin of the upper also by the side-lasting devices. Springs connected to the straps are arranged to hold them taut while permitting them thus to be forced inwardly over the insole. Since the straps in the construction shown extend between the toe former and portions of the sides of the upper, they cooperate with the toe former in wiping the upper heightwise of the last and, in fact, increase the effectiveness of the wiping action on the sides of the upper where they are located, the straps preferably being formed of textile fabric, such as canvas, adapted to act with effective friction on the fabric upper as well as to act effectively to press the margin of the upper firmly on the insole. In the construction shown the straps are also arranged to extend beyond the toe former along the sides of the upper and to be overlapped by the side-lasting devices in conforming the upper to the sides of the last, thus affording increased insurance against the formation of any wrinkles in the upper opposite the sides of the forepart of the last.

The above and other features of the invention, including various novel details of construction and combinations of parts, will now be more particularly described with reference to the accompanying drawings and thereafter pointed out in the claims.

In the drawings,

Fig. 1 is a view in front elevation of a portion of a machine in which the invention is embodied;

Fig. 2 is a plan view of a portion of the machine shown in Fig. 1, with parts broken away;

Fig. 3 is a view partly in elevation and partly in section, showing portions of the machine as viewed from the right with reference to Fig. 1, the parts being shown in the positions which they occupy prior to the wiping of the upper heightwise of the last;

Fig. 4 is a view similar to Fig. 3, showing the parts as they appear after the wiping of the upper heightwise of the last and the laying of its margin inwardly over the insole; and

Fig. 5 is a plan view, with parts broken away, illustrating conditions at the same stage in the operation of the machine as in Fig. 4.

As more fully disclosed in the above-mentioned Letters Patent, a last with an upper thereon is mounted at its heel end on a support 2 provided with a pin 4 which extends into the spindle hole in the last, the support being yieldingly compressible with the last and shoe against the resistance of a spring (not shown). At its toe end the

last is supported on an upper-engaging toe rest 6 (Figs. 3 and 4) yieldingly compressible against the resistance of a spring 8. Arranged to extend continuously around the toe end and along portions of the sides of the shoe is a toe former comprising a band 10 which may be made of comparatively hard leather or other material suitable for wiping the upper effectively heightwise of the last in response to depression of the last. Such depression of the last is effected in the power operation of the machine by a toe presser foot 12 arranged to engage the toe end of an insole on the last and by a heel presser foot (not shown) which engages the heel end of the insole. The toe presser foot 12 is supported by an arm 14, a portion of which is shown in Fig. 1, this arm being swung forwardly by the operator to a position over the shoe and being then moved downwardly by power to depress the shoe, the arm having also thereon means which need not be particularly described for controlling the margin of the toe end of the upper in the lasting operation. The toe former or band 10 is supported and controlled by means such as disclosed in Letters Patent No. 2,026,539, whereby it is held yieldingly in effective wiping engagement with the upper during the depression of the last but is permitted to yield in outward directions in response to pressure of the last and upper thereon while maintaining its conformity to the contour of the last.

After the wiping of the upper heightwise of the last by the toe former 10 as above described, the margin of the portion of the upper embraced by the toe former is laid or wiped inwardly over the insole into position to adhere to the insole by a plurality of wipers hereinafter sometimes referred to as overlaying members. The construction of these wipers and of the means for operating them is, for the most part, substantially as disclosed in Letters Patent No. 2,026,539. The wipers comprise a pair of end wiper plates 16 (Fig. 2), and a pair of side wiper plates 18 for wiping the upper inwardly along the sides only of the toe beyond the end plates. The side plates 18 are comparatively thin plates which are fast on arms 20, only one of which is shown in Fig. 2, these arms being pivotally mounted for swinging movements laterally of the shoe on a casting 22 which supports the wipers and their operating mechanism. The end plates 16 are connected together by a pin 24 for swinging movements laterally of the shoe, and in operation they are also advanced bodily lengthwise of the shoe relatively to the side plates 18 with portions of them overlapping these side plates. The end plates 16 are supported by a rack bar 26 which is slidably movable in the casting 22 and is operated thus to advance them lengthwise of the shoe. The end plates and the side plates 18 are closed laterally of the shoe by rack bars 28 also slidably movable in the casting 22. Each of these rack bars is adjustably connected to a slide 30 which is connected by a link 32 to a lever 34 pivoted at 36 on the casting 22, the lever 34 being provided with a pin 38 arranged to act through a link 40 to close the corresponding end wiper plate 16. Each lever 34 serves also to operate the corresponding side wiper plate 18 by swinging the arm 20, the lever acting on the arm through a sliding connection 42 between the lever and the arm, as fully disclosed in the last-mentioned Letters Patent. The side wiper plates 18 are positioned initially far enough apart to provide ample room between them for shoes of different widths, and the links 40 are provided with slcts 44 to receive the pins 38 and to

delay the beginning of the closing movements of the end plates 16 until the side plates have been moved into substantially as close relation to the shoe as the end plates.

For laying the margin of the upper inwardly over the insole in locations immediately beyond the ends of the side plates 18 the machine herein is provided with devices substantially like those shown in Letters Patent No. 2,026,539, except that each of these devices comprises a wiper 46 instead of a pair of rolls. Each wiper 46 is supported on a holder 48 pivotally mounted for swinging movements heightwise of the shoe on a stud 50 carried by the corresponding arm 20. Mounted between a lug 52 on the holder 48 and a lug 54 on the arm 20 is a spring 56 which tends to swing the holder about the stud 50 in the direction to depress that portion of the wiper 46 which acts on the shoe, the spring being yieldable in response to upward wedging action of the shoe on that portion of the wiper. To limit movement of the holder 48 by the spring 56 a bolt 58 extends through the spring and through openings in the lugs 52 and 54, the bolt having on its lower end a head 60 which overlaps the lug 54 and having on its upper end nuts 62 which overlap the lug 52. Each wiper 46 is provided with an upturned inner end 64 to assist in guiding it inwardly over the shoe, and to permit it to adjust itself to the contour of the shoe it is mounted for universal tipping movement on the holder 48. For this purpose there is provided a spherically curved bearing member 66 mounted on a similarly curved seat on the lower face of the holder 48 and arranged to space the wiper 46 somewhat below the holder while permitting it to tip in any direction as above described. A pin 68 having a head on its lower end engaging the wiper 46 extends upwardly through the wiper and the bearing member 66 and through an enlarged opening 70 in the holder 48, this pin being provided at its upper end with a small transverse pin 72 extending over and confining a spherically curved leaf spring 74 which rests on the upper face of the holder 48. The spring 74 accordingly tends to maintain the wiper 46 in a centralized position while permitting it to tip to adjust itself to the shoe. At its outer end the wiper 46 extends into an opening 76 in the holder 48, this opening being somewhat larger than the end of the wiper to permit the wiper to tip as above described. Relative movement of the holder 48 and the wiper 46 in response to pressure of the shoe on the lower face of the wiper is limited by contact of the outer end of the wiper with the lower wall of the opening 76, so that insurance is afforded that the wiper will apply adequate downward pressure to the margin of the upper.

The machine is further provided with means (not shown) for lasting the heel end of the shoe and with opposite side-lasting devices for lasting the sides of the shoe from the portion operated upon by the heel-lasting means to the portion operated upon by the above-described toe-lasting means. Each of the opposite side-lasting devices, the construction of which is substantially as disclosed in the previously mentioned Letters Patent No. 1,843,232, comprises a casing 78 (Figs. 1 and 5) mounted for bodily movement lengthwise of the shoe and also for swinging movement laterally of the shoe. Associated with this casing and movable with it lengthwise and laterally of the shoe are a plurality of flexible lasting straps 80, herein shown as three in number, arranged to extend heightwise of the last and to wipe the up-

per upwardly and conform it to the lateral contour of the last. The straps also extend outwardly over yieldingly controlled fingers 32, the outer end portions of which are shown in Fig. 1, and by the action of these fingers the straps are caused to lay the margin of the upper inwardly over the insole and to press it down on the insole. In the operation of the machine, as disclosed in the last-mentioned Letters Patent, the two opposite side-lasting devices are arranged to act on the shoe first along the shank portion adjacent to its heel-end portion and are thereafter moved lengthwise of the shoe to positions adjacent to the toe-lasting means and are then operated a second time to last the sides of the shoe in those locations while the toe wipers are maintained at the limits of their inward movements over the shoe.

For the purposes of the present invention, a pair of flexible straps 84, preferably made of canvas or other suitable textile fabric, are arranged to extend heightwise of the shoe between the toe former 10 and portions of the upper at the sides of the last and also to extend outwardly over the upturned ends 64 of the wipers 46. At its lower end each strap 84 is unyieldingly connected, by means of a hook 86 extending through an eyelet in the strap, to a member 88 which is part of the means for supporting the toe former 10. At the end of its outwardly extending portion each strap 84 is connected by a hook 90, a cable 92 and a hook 94 to a spring 96 the lower end of which is connected to a bracket 98 fast on the side of the previously mentioned casting 22, the cable extending over a pulley 100 mounted on a bracket 102 also supported by the casting 22. The straps 84 are arranged to be forced inwardly over the insole by the wipers 46, as illustrated in Fig. 4, so that these wipers act through the straps to lay the margin of the upper over the insole and to press it upon the insole. The straps 84 extend continuously along the upper lengthwise of the shoe into positions to be overlapped also by portions of the straps 80 of the side-lasting devices as the latter conform the upper to the sides of the last and lay its margin inwardly over the insole, as illustrated in Fig. 5. The straps 84 accordingly bridge any space which there may be between the side-lasting devices and the toe-lasting means, thus insuring that the upper will be smoothly conformed to the sides of the last and that its margin will be pressed down into position to adhere to the insole without the presence of any upstanding wrinkles. It will further be evident that, positioned as they are between the toe former and portions of the sides of the upper, the straps 84 serve also to wipe the upper heightwise of the last in those locations in response to downward movement of the last, thus increasing the effectiveness of the upwiping action in the vicinity of the heelwardly extending ends of the toe former, especially if the straps are made of textile fabric as hereinbefore described. This contributes further to improved results in the shaping of the upper tightly and smoothly over the last in close conformity to the contour of the last.

The manner of operation of the machine, in so far as its operation is of interest with reference to the present invention, will now be briefly summarized: The operator places a last having an upper mounted thereon on the heel-end support 2 with the toe end of the upper and last resting on the toe rest 6, and while holding the upper pulled closely around the heel end of the last with his fingers releases the heel-lasting mecha-

nism to cause it to move into operating position in the manner disclosed in Letters Patent No. 1,843,232. The operator then pulls the upper upwardly with his fingers at the sides of the last and releases the opposite side-lasting mechanisms to cause them to move inwardly into positions to clamp the upper against the sides of the last in the vicinity of its shank portion. Thereafter the operator places a cement-coated insole on the bottom of the last and swings the arm 14 forwardly to carry the toe presser foot 12 into position over the bottom of the shoe, as a result of which movement of the arm the power operation of the machine is started. The toe presser foot and the heel presser foot are then operated to depress the last, thus causing the side-lasting devices to wipe the upper upwardly at the sides of the last in the vicinity of the shank portion and the toe former 10 to wipe it upwardly around the toe-end portion of the last, the straps 84 having at this time also an upwiping action on the sides of the upper in the vicinity of the heelwardly extending end portions of the toe former. Substantially at the end of the downward movement of the last the side-lasting devices are operated to lay the margin of the upper over the insole and to press it down on the insole along the shank portion, after which they are swung outwardly away from the shoe and the several wipers 16, 18 and 46 are operated to wipe or lay the margin of the portion of the upper embraced by the toe former 10 inwardly over the insole and to press it upon the insole simultaneously with a corresponding wiping action of the heel-lasting means on the heel end of the upper. At this time the straps 84, which are overlapped by the wipers 46, are forced inwardly over the insole by these wipers against the resistance of the springs 96, so that the wipers 46 act through the straps to lay the upper over and press it upon the insole. Near the end of the overlaying movements of the wipers 16, 18 and 46 the toe presser foot 12 and the corresponding heel presser foot are raised enough to cause the margin of the upper to be pressed more firmly against these wipers by the spring 8 under the toe rest and the corresponding spring under the heel-end support 2. Substantially at the same time the side-lasting devices are advanced lengthwise of the shoe to positions adjacent to the toe-lasting means, after which they are again swung inwardly into engagement with the upper to conform the upper to the contour of the sides of the last and are operated to lay the margin of the upper inwardly over the insole and to press it upon the insole. As the side-lasting devices engage the sides of the shoe in this second operation the last is again depressed somewhat by the toe and heel presser feet to relieve the pressure of the toe wipers on the shoe, and in response to such depression of the last the side-lasting devices have an upwiping action on the sides of the upper. The straps 84 extend far enough along the shoe to be overlapped by the side-lasting devices in thus pressing the upper inwardly against the sides of the last and in laying its margin over the insole, as is evident by reference to Fig. 5. Any spaces between the side-lasting devices and the toe former 10 or between them and the wipers 46 are therefore bridged by the straps 84, thus insuring that the upper will be smoothly conformed to the sides of the last and that no upstanding wrinkles will be formed in the margin of the upper between the side-lasting devices and the wipers. After the second operation of

the side-lasting devices on the shoe the parts of the machine are returned to their starting positions, the shoe being released to permit its removal from the machine.

5 Having described the invention, what we claim as new and desire to secure by Letters Patent of the United States is:

1. In a lasting machine, a toe former arranged to extend around the toe end and along portions 10 of the sides of an upper on a last and to wipe the upper heightwise of the last, overlaying members for laying the margin of the portions of the upper embraced by said toe former inwardly over an insole on the last, side-lasting devices 15 for laying the margin of the upper inwardly over the insole along the sides of the last in locations beyond but adjacent to said members, and means 20 of flexible sheet material arranged to lie between the toe former and portions of the upper at the sides of the last for wiping the upper heightwise of the last and also to extend continuously along the upper into positions to be overlapped both by said overlaying members and by the side-lasting devices and to be pressed against the margin of 25 the upper by said members and devices as they lay the margin upon the insole.

2. In a lasting machine, a toe former arranged to extend around the toe end and along portions 30 of the sides of an upper on a last and to wipe the upper heightwise of the last, overlaying members for laying the margin of the portions of the upper embraced by said toe former inwardly over an insole on the last, side-lasting devices for conforming the upper to the sides of the last 35 and for laying its margin inwardly over the insole in locations beyond but adjacent to said members, and means of flexible sheet material arranged to lie between the toe former and portions of the upper at the sides of the last for wiping the upper heightwise of the last and also to extend beyond the toe former into positions to be overlapped by the side-lasting devices in conforming the upper to the sides of the last and to be 40 pressed against the margin of the upper both by said devices and by the overlaying members in laying the margin of the upper upon the insole.

3. In a lasting machine, a toe former arranged to extend around the toe end and along portions 45 of the sides of an upper on a last and to wipe the upper heightwise of the last, overlaying members for laying the margin of the portions of the upper embraced by said toe former inwardly over an insole on the last, side-lasting devices for laying the margin of the upper inwardly over the insole along the sides of the last in locations 50 beyond but adjacent to said members, flexible straps arranged to occupy positions between the toe former and portions of the upper at the sides of the last for wiping the upper heightwise of the last and also to extend continuously along the upper into positions to be overlapped both by said overlaying members and by the side-lasting devices and to be pressed against the margin of 55 the upper by said members and devices as they lay the margin upon the insole, and spring means connected to said straps for holding them taut while permitting them to be forced inwardly over the insole.

4. In a lasting machine, a toe former arranged 60 to extend around the toe end and along portions of the sides of an upper on a last and to wipe the upper heightwise of the last, overlaying members for laying the margin of the portions of the upper embraced by said toe former inwardly over an insole on the last, side-lasting devices 65

for conforming the upper to the sides of the last and for laying its margin inwardly over the insole in locations beyond but adjacent to said members, and flexible straps arranged to occupy positions between the toe former and portions of the upper 5 at the sides of the last for wiping the upper heightwise of the last, said straps extending lengthwise of the last beyond the toe former into positions to be overlapped by the side-lasting devices in conforming the upper to the sides of 10 the last and extending also into positions to be overlapped both by said overlaying members and by the side-lasting devices opposite the margin of the upper and to be pressed against the margin of the upper by said members and devices 15 as they lay the margin upon the insole.

5. In a lasting machine, a toe former arranged to extend around the toe end and along portions of the sides of an upper on a last and to wipe the upper heightwise of the last, overlaying members movable to lay the margin of the portions of the upper embraced by said toe former inwardly over an insole on the last, side-lasting devices movable to lay the margin of the upper inwardly over the insole along the sides of the last in locations beyond but adjacent to said overlaying members after said members have been moved inwardly over the insole, and flexible straps arranged to occupy positions between the toe former and portions of the upper at the sides 30 of the last for wiping the upper heightwise of the last, said straps extending beyond the toe former into positions to be forced inwardly over the insole and pressed against the margin of the upper by said overlaying members and also to 35 be overlapped and pressed against the margin of the upper thereafter by the side-lasting devices.

6. In a lasting machine, a toe former comprising a flexible band arranged to extend continuously around the toe end and along portions 40 of the sides of an upper on a last and to wipe the upper heightwise of the last, wipers movable to wipe the margin of the portions of the upper embraced by said band inwardly over an insole on the last into position to adhere to the insole, 45 side-lasting devices movable to lay the margin of the upper inwardly over the insole along the sides of the last in locations beyond but adjacent to said wipers after the wipers have been moved inwardly over the insole, and flexible straps arranged to occupy positions between the toe former and portions of the upper at the sides only of the last for wiping the upper heightwise of the last, said straps extending beyond the toe former into positions to be forced inwardly over 50 the insole and pressed against the margin of the upper by said wipers and also to be overlapped and pressed against the margin of the upper thereafter by the side-lasting devices.

7. In a lasting machine, a toe former comprising a flexible band arranged to extend continuously around the toe end and along portions of the sides of an upper on a last and to wipe the upper heightwise of the last, wipers movable to 60 wipe the margin of the portions of the upper embraced by said band inwardly over an insole on the last into position to adhere to the insole, side-lasting devices movable to lay the margin of the upper inwardly over the insole along the sides of the last in locations beyond but adjacent 65 to said wipers after the wipers have been moved inwardly over the insole, flexible straps of textile fabric arranged to occupy positions between the toe former and portions of the upper at the sides only of the last for wiping the upper height- 70 75

- wise of the last, said straps extending beyond the toe former into positions to be forced inwardly over the insole and pressed against the margin of the upper by said wipers and also to be overlapped and pressed against the margin of the upper thereafter by the side-lasting devices, and spring means connected to said straps for holding them taut while permitting them to be forced inwardly over the insole by the wipers.
8. In a lasting machine, a toe former arranged to extend around the toe end and along portions of the sides of an upper on a last and to clamp the upper against the last, overlaying members movable to lay the margin of the portions of the upper embraced by said toe former inwardly over an insole on the last, side-lasting devices for laying the margin of the upper inwardly over the insole along the sides of the last in locations beyond but adjacent to said overlaying members, and flexible straps arranged to be clamped by the toe former against portions of the upper at the sides of the last, said straps extending beyond the toe former into positions to be overlapped both by said overlaying members and by the side-lasting devices and to be pressed against the margin of the upper by said members and devices as they lay the margin upon the insole.
9. In a lasting machine, a toe former arranged to extend around the toe end and along portions of the sides of an upper on a last and to clamp the upper against the last, overlaying members movable to lay the margin of the portions of the upper embraced by said toe former inwardly over an insole on the last, side-lasting devices movable to lay the margin of the upper inwardly over the insole along the sides of the forepart of the last in locations beyond but adjacent to said overlaying members after said members have been moved inwardly over the insole, and flexible straps arranged to be clamped by the toe former against portions of the upper at the sides only of the last, said straps extending beyond the toe former into positions to be forced inwardly over the insole and pressed against the margin of the upper by said overlaying members and also to be overlapped and pressed against the margin of the upper thereafter by the side-lasting devices.
10. In a lasting machine, a toe former arranged to extend around the toe end and along portions of the sides of an upper on a last and to wipe the upper heightwise of the last by contact therewith, said toe former having associated therewith between it and the upper at each side only of the last a flexible member of textile fabric arranged to be pressed against the upper by the toe former and to wipe the upper heightwise of the last in that location.
11. In a lasting machine, a toe former comprising a flexible band arranged to extend around the toe end and along portions of the sides of an upper on a last and to wipe the upper heightwise of the last, said band having associated therewith at each side only of the last a flexible strap arranged to extend heightwise of the last between the band and the upper and to wipe the upper heightwise of the last in that location.
12. In a lasting machine, a toe former comprising a flexible band arranged to extend around the toe end and along portions of the sides of an upper on a last and to wipe the upper heightwise of the last, and flexible straps of textile fabric arranged to extend heightwise of the last between said band and the upper at the opposite sides only of the last and to be pressed against

the upper by the band for wiping the upper heightwise of the last in those locations.

13. In a lasting machine, a toe former comprising a flexible band arranged to extend around the toe end and along portions of the sides of an upper on a last and to wipe the upper heightwise of the last, flexible straps arranged to extend heightwise of the last between said band and the upper at the opposite sides only of the last for wiping the upper heightwise of the last in those locations, portions of said straps beyond the band being arranged to extend outwardly widthwise of the last, spring means connected to the outwardly extending end portions of the straps for holding the straps under tension, and means for anchoring the other ends of the straps.

14. In a lasting machine, overlaying members movable to lay the margin of an upper around the toe end of a last inwardly over an insole on the last, side-lasting devices movable to lay the margin of the upper inwardly over the insole along the sides of the forepart of the last in locations beyond but adjacent to said overlaying members after said members have been moved inwardly over the insole, and means of flexible sheet material arranged to bridge any spaces between said overlaying members and the side-lasting devices opposite the margin of the upper and to be overlapped and pressed upon the margin of the upper by both said members and devices in laying the margin upon the insole.

15. In a lasting machine, overlaying members movable to lay the margin of an upper around the toe end of a last inwardly over an insole on the last, side-lasting devices movable to lay the margin of the upper inwardly over the insole along the sides of the forepart of the last in locations beyond but adjacent to said overlaying members after said members have been moved inwardly over the insole, flexible straps arranged to bridge any spaces between said members and devices opposite the margin of the upper and to be forced inwardly over the insole and pressed against the margin of the upper by said members, and spring means connected to said straps and yieldable to permit them thus to be forced inwardly over the insole, said straps extending far enough lengthwise of the last to be overlapped and pressed upon the margin of the upper by the side-lasting devices as they lay the margin upon the insole.

16. In a lasting machine, overlaying members for laying the margin of an upper around the toe end of a last inwardly over an insole on the last, side-lasting devices comprising flexible straps for laying the margin of the forepart of the upper inwardly over the insole along the sides of the last in locations beyond but adjacent to said members, and additional flexible straps arranged to bridge any spaces between said overlaying members and side-lasting devices and to be overlapped and pressed upon the margin of the upper by said overlaying members, said additional straps being arranged also to be overlapped and pressed upon the margin of the upper by the straps of the side-lasting devices.

17. In a lasting machine, wipers movable to wipe the margin of an upper inwardly over an insole on a last around the toe end and along portions of the sides of the last, side-lasting devices movable to lay the margin of the forepart of the upper inwardly over the insole along the sides of the last in locations beyond but adjacent to said wipers, flexible straps arranged to extend heightwise of the last and outwardly over

portions of said wipers and to be forced inwardly over the insole and pressed upon the margin of the upper by the wipers, and springs connected to the outwardly extending portions of said straps and yieldable to permit them thus to be forced inwardly over the insole, the straps ex-

tending continuously lengthwise of the last into positions to be overlapped and pressed upon the margin of the upper also by the side-lasting devices.

LEROY FARNUM.
LLOYD G. MILLER.
